UNITED STATES PATENT OFFICE

CLIFFORD H. McCASLIN, OF OAKLAND, CALIFORNIA

FOLDING TABLE

Application filed July 2, 1928. Serial No. 289,888.

This invention is an improvement over the form of the device shown in my co-pending application Serial No. 262,864 filed March 19, 1928. In said application I showed a bracing member for holding two folding legs in operative position, this bracing member also being used as a cover for sealing and locking in place the folding legs when folded.

In the present invention I dispose the bracing member against the underside of the table top when not in use and then swing the legs over this member and secure the legs in inoperative position by any suitable fastening means. In the present invention, the table top is provided with an apron that prevents the bracing member from sliding out when the table is folded.

A further object of my invention is to provide a device of the type described which is extremely simple in construction and which is durable and efficient for the purpose intended.

Other objects and advantages will appear as the specification proceeds, and the novel features will be particularly pointed out in what I hereinafter claim.

My invention is illustrated in the accompanying drawing forming a part of this application, in which

20 Figure 1 is a side elevation of the device; Figure 2 is an end elevation;

Figure 3 shows the table folded and a portion of the apron broken away for clarity;

25 Figure 4 is a top plan view with a portion of the table top broken away; and

Figure 5 is an enlarged detail view.

In carrying out my invention I provide a table top 1 that may be of any shape desired. I have shown the top rectangular in shape, 40 and have shown an apron 2 extending around the four sides of the top.

Folding legs 3 and 4 are pivotally secured to the top. It will be noted that the leg 3 is shorter in length than the leg 4 and is hinged 45 at 5 to the underside of the lowermost block of a series of blocks 6. The blocks are secured to the underside of the table top 1 and are disposed inside of the apron 2.

The leg 4 is hinged at 7 to the underside 50 of a block 8. Both legs are substantially of

the same width as the width of the table top.

I provide a bracing member 9 for holding the legs in operative position. This member is similar to the bracing member shown in my co-pending application, and is provided with hand holes 10 for permitting it to be moved into and out of position easily. At the side edges of the member I mount guide strips 11 of the shape shown in Figure 5. These strips are slidably received in channels 12, and in this way the brace is secured to the legs and prevents the wobbling of the latter.

In folding the device, the member 9 is removed and is then placed against the underside of the table top as shown in Figure 3. The legs 3 and 4 are now folded down upon the bracing member 9, the leg 4 being disposed adjacent to the member and the leg 3 being disposed on top of the leg 4. Any suitable fastening means may be used for securing the leg 3 in folded position. I show snap fasteners 13 carried by the legs for this purpose. The apron prevents the brace 9 from sliding out.

Although I have shown and described one embodiment of my invention, it is to be understood that the same is susceptible of various changes, and I reserve the right to employ such changes as may come within the scope of the invention as claimed.

I claim:

1. A folding-table comprising a one piece top, aprons disposed around the sides of the table and with the top forming a recess, legs of substantially the width of the table being hinged to the underside of the top so as to be swingable into a position within the recess, a bracing member of substantially the same width as that of the recess and a length equal to the distance between the two legs when in operative position, and cooperating means carried by the inner surfaces of said legs and the edges of said bracing member for securing them together, said bracing member being received in the recess and held in place by the apron and legs when the latter are folded.

2. A folding table comprising a top, an apron depending therefrom and forming a recess with the top, legs hinged to said top

and adapted for swinging into the confines of the recess, and a bracing member for holding said legs in extended position and arranged to be introduced into the recess when the table is being folded with the apron serving as a retaining wall therearound; said legs, when folded, overlying the member for holding the latter in the recess.

3. A folding table comprising a top, an apron depending therefrom and forming a recess with the top, legs hinged to said top and adapted for swinging into the confines of the recess, a bracing member for holding said legs in extended position and arranged to be introduced into the recess when the table is being folded with the apron serving as a retaining wall therearound; said legs, when folded, overlying the member for holding the latter in the recess, and means for securing the legs in folded position.

4. A folding table comprising a top, an apron depending therefrom and forming a recess with the top, legs hinged to said top and adapted for swinging into the confines of the recess, and a bracing member for holding said legs in extended position, and arranged to be introduced into the recess when the table is being folded with the apron serving as a retaining wall therearound; said legs, when folded, overlying the member for holding the latter in the recess and forming substantially a closure over the mouth of the recess.

5. A folding table comprising a top, an apron depending therefrom and forming a recess with the top, legs hinged to said top and adapted for swinging into the confines of the recess, a bracing member for holding said legs in extended position and arranged to be introduced into the recess when the table is being folded with the apron serving as a retaining wall therearound, said legs, when folded, overlying the member for holding the latter in the recess, and fastening means for automatically engaging and securing the legs in folded position when the latter are moved into an inactive position.

CLIFFORD H. McCASLIN.
